GEORGE McCALL, OF WOODSIDE, AND JOSIAH E. REID, OF NEW YORK, N. Y., AS
SIGNORS TO INTERNATIONAL MOTOR COMPANY, OF NEW YORK, N. Y., A COR-
PORATION OF DELAWARE.

CONTAINER BOGIE.

Application filed December 21, 1926. Serial No. 156,218.

With improved varieties of transportation as found at the present time there has arisen the difficulty of economically handling the great volume of freight and suitably transferring it from one system or road, to another. It has heretofore been proposed to provide great numbers of standard containers in which may be placed the freight to be handled and which may be transferred as a unit, from 5 one carrier to another. This reduces the amount of handling necessary and enables it to be done with less expense where cranes, ramps and suitable apparatus have been installed at the terminus to handle such containers.

The purpose of the present invention is to provide an attachment for unit containers of the above type which will convert them from stationary box like structures to a unit 20 which can be easily moved about a platform and on and off of the carrier. It is necessary that the device be small and easily handled and, above all, readily applied to, or removed from, the desired container.

In such a stationary box-like container having no rollers or wheels permanently attached to its bottom it is desirable that the container be readily transportable from the platform of the consignor to a motor truck, 30 and, upon final delivery, from a motor truck to the platform of the consignee. It may be more convenient at railroad terminals to handle the containers by cranes, etc., which are permanently installed. The present invention enables such a container to be used and provides a means for readily transporting the same.

It will thus be seen that the object of the present invention is to provide an attachment 40 for a standard unit container which may be readily applied to, and removed from the container to render the same easily transportable in the operation of loading or unloading from carriers. By relieving the containers of rollers, the weight thereof is distributed over a large bearing area which is highly desirable in the transportation of the containers.

Reference will now be had to the accompanying drawings for a more detailed description, wherein like reference characters designate like parts, and wherein:

Figure 1 is an elevation, partly broken away and in section, showing the preferred form of the invention.

Figure 2 is a side elevation, partly broken

away and in section, of the embodiment shown in Figure 1.

Figure 3 is a section taken on line 3—3 of Figure 1 showing the ratchet mechanism.

Figure 4 is an elevation, partly in section, 60 showing a modified form of the invention.

Figure 5 is a side elevation showing a pair of the devices of Figure 4 as applied to the side of the container.

In the drawings *a* represents a container 65 of any desired form now in use not permanently fitted with wheels, and provided with a lug *d* which has a recess *d*¹ and at its lower portion, co-operating lugs *d*² provided with flanges *d*³. A bracket *e* is formed at its lower 70 extremity with a vertical bearing *e*' which carries a caster *f* having an inverted U-shaped portion *f*'. Between the lugs of the U-shaped portion is mounted a roller *f*² and the caster is secured within the bearing by means of nut *f*³ and washer *f*⁴. A recess *f*⁵ is formed in the upper portion of the caster, and a pin *f*⁶, adjusted by a knurled knob *f*⁷ is carried in the bracket member *e*. Spring *f*⁸ normally urges the pin *f*⁶ into engaging position with the recess *f*⁵. A pin *f*⁹ is carried with the pin shaft *f*¹⁰ and is adapted to be received in the slot *f*¹¹ formed in the bracket *e*. By means of this structure the caster can be locked against rotation. Advantage of 80 this feature may be taken in two ways. By locking all four wheels it is possible to remove the container from a motor truck by the ramp track method, since the bogie or truck member, can be made with wheels of 85 the proper gage to engage the ramp track. Furthermore, by locking the two rear wheels, the container can be steered more easily when it is being pushed or moved in a desired direction. 95

At the lower portion of the bracket *e* are formed oppositely disposed wing-shaped flanges *g* which are formed upon the bracket to be normally above the flanges *d*³ of the container. When the container is lifted from the floor, the flanges *g* engage behind the flanges *d*³ to secure the bracket in position against the container.

At the upper portion of the bracket, a rotatable nut *h* is provided having a bevel gear *h*' at its upper extremity and having an internally threaded portion *h*². Within this nut is carried a screw *i* which is operated by the nut, and which has an axial groove *i*' adapted to be engaged by a key *i*² mounted 110

upon a pin i^3 which is carried by the bracket e . This structure prevents the screw from turning and results in its upward movement upon rotation of the nut h .

Adjacent the nut h and formed with the bracket e , is provided an extension j formed with a longitudinal bearing j' adapted to receive a shaft j^2 . At the end of the shaft adjacent the nut h , is mounted a bevel gear j^3 engaging the bevel gear h' . The shaft j^2 is formed with a recess j^4 to be engaged by a crank k' in a well known manner. At the end of the bearing j' , is provided a housing l adapted to receive a ratchet wheel l' which is mounted upon the shaft j^2 . In the lower portion of the housing l is provided a pin l^2 operated by a knurled nut l^3 and pressed against the ratchet wheel by spring l^4 . It will be seen that the pin may be lifted from the ratchet wheel and turned through 180° to provide a ratchet effect in the opposite direction.

At the top of the screw i is formed a head i^4 and a nose i^5 which is adapted to be received in the recess d' .

In Figures 4 and 5, a modified form of the invention is shown. In this form, a designates a container provided with blocks or channels a' at the bottom and with timber lengths a^2 to keep the container off the floor. The channels a' may be secured to the containers as by bolts and nuts a^3 .

On the side of the containers and above each channel piece, are secured suitable brackets a^4 , between which and the container, a lifting arm may be received.

The truck member consists of a housing b , provided at its outer side with a bracket extension b' , which, with the housing, forms a U -shaped recess to receive a roller b^2 . The roller is mounted on the shaft b^3 extending between the two U -members.

Slidably mounted within the housing is a lifting rod c provided with a horizontal hook c' which engages the channel or block a' when it is raised. Rod c has serrations or ratchet elements c^2 on its back and an upwardly extending nose c^3 which is received in the recess of the bracket, as previously noted. To prevent the bogie or truck member from slipping down and disengaging the container when the latter is moved over rough and uneven floors, provision is made for securing the bogie to the container. Thumb screw m is provided to prevent relative movement between lifting member c and housing b when the bogie is in operative position. Co-operating holes o and p are provided in the nose of the lifting member and the bracket a^4 and to the housing is secured, as by a chain, a pin n which is received in the holes o and p and prevents the disengagement of the bogie from the container. After the bogie has been applied and the lifting member raised to the desired height, the pin n is inserted in the

holes o and p and the thumb screw m tightened. This will prevent the bogie from disengaging the container.

At b^4 in housing b there is pivoted a crank d which receives a handle d' in the usual manner. A pawl e is also pivoted at b^4 and engages the ratchet teeth c^2 to hold the rod c in a lifted position. On the lower end of crank d a pawl f is provided which likewise engages the teeth and through application of suitable force on the lever d' , lifts the rod. The elements just described constitute the parts of any well known type of jack and form no part of this invention. Furthermore, the roller previously described may be a swivel caster or other similar form of mechanism without departing from the scope of this invention.

In operation, the device is placed against the container so that lifting rod c with its hook c' and nose c^3 will be in such position, that upon raising the rod, the ends will engage their respective seats and lift the container.

The present invention embodies a device which may be used on containers of the commercial form and size to enable them to be readily handled. It is light and strong and can be readily put in use or removed and can be carried by the motor truck to each warehouse. A further advantage of this type of bogie is that very little pressure is brought to bear on the side of the container but is applied underneath where it is best able to receive the pressure.

Obviously the devices may be arranged in pairs to form a unitary and staple support for one side of the container.

What we claim is:

1. In an attachment for unit containers, a housing, roller means mounted at the lower extremity thereof to facilitate movement over surfaces, a lifting member mounted in the housing, means on the housing to engage cooperating means on the container to prevent substantial lateral movements thereof in any direction with respect to the lifting member, means on the lifting member to engage cooperating means on the container to support it, and means for lifting said lifting member.

2. In attachments for unit containers, a housing, a roller mounted at the lower extremity thereof, a lifting member mounted within the housing, a lug mounted on the container and provided with a flange, a flange on the housing for engaging the flange on the lug, an upwardly extending nose on the upper end of said member for engaging the side of said container, means on the container adapted to be engaged by the nose, and means for lifting said lifting member.

3. In attachments for unit containers, a bracket, said bracket having a downwardly extending U -shaped portion at the lower end

thereof, a roller mounted in said U-shaped portion, a lifting member mounted within the bracket, means for engaging the container to be lifted near the bottom thereof, an upwardly extending nose on the upper end of the lifting member for engaging the side of said container, and means for lifting said last named member.

55

in the bearing, spaced lugs mounted on the container and provided with flanges, flanges on the lower portion of the bracket for engaging the flanges of the lugs, a nut mounted rotatably in the upper portion of the bracket, a screw threaded into the nut and actuated thereby, said screw having a groove 60 cut axially therein, means upon the screw

4. In attachments for unit containers, a bracket, said bracket having a downwardly extending U-shaped portion at the lower end thereof, means to mount said portion rotatably, a roller mounted in said U-shaped portion, a lifting member mounted within the bracket, a lug mounted on the container and provided with a flange, a flange on the bracket for engaging the flange on the lug, an upwardly extending nose on the upper end of the lifting member for engaging the side of said container and means for lifting said last named member. 10

5. In attachments for unit containers, a bracket, a vertical bearing formed in the lower portion of the bracket, a caster carried in the bearing, spaced lugs mounted on the container and provided with flanges, flanges on the lower portion of the bracket for engaging the flanges of the lugs, a nut mounted rotatably in the upper portion of the bracket, a screw threaded into the nut and actuated thereby, means upon the screw for engaging the container means to prevent the screw from rotating, and means to rotate the nut. 20

40

45

50

6. In attachments for unit containers, a bracket, a vertical bearing formed in the lower portion of the bracket, a caster carried in the bearing, spaced lugs mounted on the container and provided with flanges, flanges on the lower portion of the bracket for engaging the flanges of the lugs, a nut mounted rotatably in the upper portion of the bracket, a screw threaded into the nut and actuated thereby, means upon the screw for engaging the container, means to prevent the screw from rotating, an extension formed with the bracket, a shaft rotatably mounted in the extension, co-operating gears on the shaft and screw, and means to rotate the shaft. 15

7. In attachments for unit containers, a bracket, a vertical bearing formed in the lower portion of the bracket, a caster carried for engaging the container, a key engaging the groove to prevent rotation thereof, an extension formed with the bracket, a shaft rotatably mounted in the extension, co-operating gears on the shaft and screw, and means to rotate the shaft. 10

8. In attachments for unit containers, a bracket, a vertical bearing formed in the lower portion of the bracket, a caster carried in the bearing, spaced lugs mounted on the container and provided with flanges, flanges on the lower portion of the bracket for engaging the flanges of the lugs, a nut mounted rotatably in the upper portion of the bracket, a screw threaded into the nut and actuated thereby, said screw having a groove cut axially therein, means upon the screw for engaging the container, a key engaging the groove to prevent rotation thereof, an extension formed with the bracket, a shaft rotatably mounted in the extension, co-operating gears on the shaft and screw, a ratchet wheel on the shaft, a spring pressed adjustable pawl engaging the wheel, means to rotate the shaft and means to lock the caster against rotation. 15

9. In attachments for unit containers, a bracket, a vertical bearing formed in the lower portion of the bracket, a caster carried in the bearing, spaced lugs mounted on the container and provided with flanges, flanges on the lower portion of the bracket and positioned normally above the lugs for engaging the flanges thereof when the container is lifted, a nut mounted rotatably in the upper portion of the bracket, a screw threaded into the nut and actuated thereby, means upon the screw for engaging the container, means to prevent the screw from rotating, and means to rotate the nut. 20
